United States Patent Office.

GERHARD WINTER, OF NEW YORK, N. Y.

Design No. 3,566, dated June 29, 1869.

DESIGN FOR A SHOW-CASE.

The Schedule referred to in these Letters Patent and making part of the same.

To all whom it may concern:

Be it known that I, GERHARD WINTER, of the city, county, and State of New York, have invented a new and original Design for a Show-Case; and I do hereby declare the following to be a full, clear, and exact description thereof, which will enable those skilled in the art to make and use the same, reference being had to the accompanying drawing, forming part of this specification, in which—

Figure 1 represents a perspective view of this design.

Figure 2 is an end view of the same.

Similar letters indicate corresponding parts.

This invention relates to a design for show-case, the

distinguishing features of which are the inclined panels *a b* joined together at an oblique angle, as shown.

By these inclined panels a show-case of a novel and pleasing appearance is produced.

What I claim as new, and desire to secure by Letters Patent, is—

The design for a show-case, as shown and described.

This specification signed by me, this 27th day of May, 1869.

GERHARD WINTER.
